UNITED STATES PATENT OFFICE

JOHN A. OWEN, OF ALVIN, TEXAS

INCINERATOR

Application filed March 22, 1927. Serial No. 177,263.

This invention relates to new and useful improvements in an incinerator.

One object of the invention is to provide an improved type of incinerator having a main furnace in which garbage and the like may be consumed, with an auxiliary combustion chamber above the furnace into which additional air is admitted which will cause the complete consumption of unconsumed gases and other matter not completely consumed in the furnace thus eliminating all odors usually given off from incinerators.

Another object of the invention is to provide an incinerator of the character described whose walls are double throughout with air circulating channels or passageways between said walls, the inner walls being formed of firebrick and the construction being such that any of the interior walls may be removed and replaced without interfering with any of the other walls of the incinerator.

A further object of the invention is to provide an incinerator having the usual shaker grates at the bottom for the reception and support of solid garbage and a liquid receptacle, at one side, for the reception and consumption of liquid garbage, with a suspending rack, or water grate, above the shaker grates provided to receive and suspend solid garbage to the end that the same may be quickly dried out and partly consumed and then delivered to the lower or shaker grates where it is completely consumed.

A still further object of the invention resides in the provision of means whereby water may be circulated through said rack and through the delivery chute leading thereto, to the end that they will not be quickly burned out.

A further feature of the invention resides in the provision of suitable inlet shutters, with means for opening and closing the same, providing means whereby the delivery of the various kinds of garbage into the furnace may be facilitated.

A still further feature of the invention resides in novel means for delivering the ashes, and other solid products of combustion from the furnace to an accessible place on the outside thereof.

With the above and other objects in view the invention has particular relation to certain novel features of construction, operation and arrangement of parts, an example of which is given in this specification and illustrated in the accompanying drawings, wherein:

Figure 1 shows a vertical sectional view of the incinerator.

Figure 2 shows a cross sectional view taken on the line 2—2 of Figure 1.

Figure 3 shows a cross sectional view taken on the line 3—3 of Figure 1.

Figure 4 shows a fragmentary front elevation, and

Figure 5 shows a fragmentary cross sectional view, taken on the line 5—5 of Figure 3.

Referring now more particularly to the drawings, wherein like numerals of reference designate similar parts in each of the figures, the numeral 1 designates the outside walls of the incinerator furnace, which has an inwardly extending ledge 1' at the upper end, and which may be formed of concrete, brick, or other suitable material and the interior of which is preferably, though not necessarily, circular in contour and the numeral 2 designates the inside walls of the furnace which are preferably composed of fire brick and are spaced from the outside walls to provide an air circulating chamber 3 all the way around between said walls. This circulating space is closed above by the ledge 1', and below by a corresponding ledge but has the air inlet ports 4 through the outer wall at the bottom, through which air may be admitted into space 3 and the outlet ports 5 through the inner wall at the top, through which the air may be delivered from the space 3 into the upper part of the furnace proper.

Mounted on the ledge 1' of the furnace proper there is a converging smoke stack also formed of outer and inner walls 6 and 7, which are spaced apart to form an air circulating passageway 8 between them. These walls 6 and 7 may be composed of any suitable material, the outer wall being preferably of concrete or common brick, and the inner wall being preferably of fire brick, and the outer

wall 6 has the air inlets 9 opening into the lower end of the space 8 providing for the circulation of air up through said space 8. These air circulating spaces 3 and 8 serve to 5 keep the outside walls of the incinerator from becoming excessively hot, and also permit the expansion and contraction of the inner walls without affecting the outer walls.

Within the smoke stack and mounted on 10 the upper end of the ledge 1' of the furnace proper there is a baffle wall 10 which is preferably frusto-conical in general contour forming a flue and above this baffle wall within in the smoke stack there is thus provided, a 15 combustion chamber 11.

The main portion of the garbage will be 20 consumed in the furnace, as hereinafter explained, but unconsumed carbon, as well as unconsumed gases passing upwardly through the flue 10 will be mixed with additional air 25 flowing in through the ports 5 and this additional air will result in the complete consumption in combustion chamber 11 of all unconsumed matter to the end that there will be practically no odorous fumes issuing out 30 of the smoke stack. The inner walls 2, 7, and 10 are independently supported so that any one may be removed and replaced without removing any of the other walls of the incinerator.

The furnace is equipped with a suitable 35 burner, a conventional oil burner as 12 being shown, and beneath the burner the furnace is equipped with shaker grates, as 13, 13, which may be agitated, through the conventional 40 outside hand levers 14, to shake the ashes downwardly into the ash pit 15. The bottom of this pit converges toward a longitudinal central line and beneath the pit there is an endless apron 16 for conveying out the 45 ashes and which includes a suitable sprocket chain 17 operable over the end sprocket wheels 18, 18, which are fixed on suitable rotatable shafts 19, 19, one of which may be driven in any suitable manner so as to drive 50 the belt like apron 16 in the direction indicated by the arrow in Figure 1. There is a similar endless belt like conveyor 16' located between and, whose upper side is, on substantially a common plane with the grates 13 for receiving and conveying out unconsumable refuse which collects on the grates.

Above the grate there are suitable openings 55 through the furnace wall which are normally closed by the shutters 21, providing for access into the furnace for stoking purposes and beneath the grates 13 are the openings 22 provided with suitable shutters 23 for access to the furnace beneath said grates. 60 These openings 20 and 22 may be lined with metal or other suitable material, as desired, and the ashes and other refuse reaching the conveyors 16, 16' will be delivered thereby outside of the furnace to an accessible place.

An inlet chute 24 is provided whose upper

end is normally closed by the upwardly opening shutter 25 and a cable 26 is attached, at one end, to the shutter and operates over an overhead pulley 27 by means of which the shutter 25 may be raised to admit liquid garbage and the lower end of this chute is aligned over a receptacle 28 located opposite the shaker grates 13 within the furnace. The bottom of this receptacle declines toward the adjacent wall of the furnace so that the liquid 70 garbage will be retained therein until it is evaporated, and the solid portions thereof consumed. The shutter 25 is opened to admit the liquid garbage and then immediately closed so as to tightly close the furnace and 75 also prevent the escape of smoke and fumes. Above the inlet end of the chute 24 the furnace is provided with an inlet opening 29 which is normally closed by the vertically movable shutter 30. This shutter moves in 80 the side tracks 31, 31, secured to the outside of the furnace and balance cables 32, 32, are connected at one end to the shutter 30, and operated over the overhead pulleys 33, 33, and their other ends carry the weights or 85 balances 34, 34. Shutter 30 may be elevated for the admission of solid garbage and then immediately closed. This garbage will pass down over the inwardly declining chute 35 and on to the downwardly declining rack 36 90 and be there retained until it is dried and partly consumed and the unconsumed portions thereof will be gradually forced down by the additional oncoming garbage on to the grates 13 and will be sufficiently dry to readily burn and this will prevent the congestion of wet garbage into a mass on said grates and will facilitate the complete consumption of the garbage.

The chute 35 is composed of metal and has 95 an internal water circulating chamber 37 therein and the rack 36 is preferably composed of parallel tubing whose respective ends are connected into the manifolds 38 and 39, the former of which is connected with 100 the bottom of the water tank 40, through the pipe 41 and the latter of which is connected with said tank through the pipe 42. Water is thus circulated through the rack 36. The manifold 39 also has the ports 43 leading into the chamber 37 so that said water may 105 also circulate through said chamber and out through the pipe 44 which is connected into the pipe 42. Thus cooling fluid is circulated, not only through the rack 36 but also 110 through the chute 35 to the end that these parts will not be quickly burned out by the intense heat in the furnace.

What I claim is:—

1. An incinerator including a furnace, and 115 a smoke stack above the furnace, said furnace and smoke stack having double walls throughout with separate air spaces between said walls, said spaces having air inlets at their 120 lower ends and said furnace having an air 125

inlet from its wall space at its upper end, and baffle walls above the furnace inlet whose walls are inclined inwardly and upwardly, disposed within the smoke stack above the furnace.

5 2. An incinerator including a furnace having a smoke stack, a grate therein, a declining garbage retaining rack in the furnace above the grate, a chute over which garbage may be delivered onto said rack, said rack and chute having internal fluid passageway, means for circulating a cooling fluid through said passageways, a liquid receptacle at the bottom of the furnace, adjacent one wall thereof, and an inlet chute, under the garbage delivery chute, and whose discharge end is over the liquid receptacle, said receptacle being open at the top.

10 3. An incinerator including an outer furnace wall having an inwardly extending support at its upper end and an inner wall independent of and spaced from the outer wall extending up to said support, said outer wall having an inlet port leading into the space between said walls, a smoke stack above the furnace mounted on said support, and comprising an outer wall, an independent inner wall spaced from the outer wall, an upwardly converging baffle wall mounted within the

15 smoke stack on said support, said furnace having air inlet ports beneath the baffle wall and said smoke stack having an inlet port leading into the lower part of the space between its walls.

20 4. An incinerator including a furnace and a smoke stack leading upwardly therefrom, a grate within said furnace, a pair of endless apron-like conveyors disposed one above the other, one of said conveyors being disposed beneath the grate and the other being mounted to travel flush with the upper surface of the grate.

25 5. An incinerator including a furnace, a smoke stack leading upwardly from and mounted on the furnace, said furnace and smoke stack having double walls throughout forming spaces between them, a baffle wall mounted on the furnace wall and disposed between the furnace and smoke stack forming in effect two combustion chambers, one beneath and the other above the baffle wall, said wall having a restricted passageway therethrough, the furnace having inlet air ports adjacent and beneath said baffle wall, there being also air ports leading into the space between the smoke stack walls.

30 6. An incinerator including a furnace having outside and inside walls spaced apart forming a space between them, inwardly extending upper and lower ledges closing the upper and lower ends of the space, an inlet port leading into said space at the bottom, the inside wall having a plurality of outlet ports around the furnace leading from said space into the upper part of the furnace, a smoke

stack mounted on said upper ledge, having outer and inner walls, spaced apart forming an air passageway between them, having an inlet port near its lower end, an upwardly converging annular baffle wall within the smoke stack whose lower end rests on said upper ledge.

35 7. A garbage incinerating plant including in combination, a garbage receiving housing, an incinerator and a water supply source, two garbage holding means located in the incinerator in respectively different planes for receiving and retaining garbage in position to be consumed by combustion, one of which holding means is hollow, a hollow chute leading from the housing to direct garbage from the latter on to one of said holding means, means to change the flow of garbage to the other holding means, and water circulating pipes connecting the source of supply with said hollow holding means and chute.

In testimony whereof I have signed my name to this specification.

JOHN A. OWEN.
